STARTING DEVICE FOR INTERNAL-COMBUSTION ENGINES.

1,039,864.

Specification of Letters Patent.

Patented Oct. 1, 1912.

Application filed February 5, 1907. Serial No. 355,959.

To all whom it may concern:

Be it known that I, WILLIAM B. SMITH WHALEY, a resident of Boston, in the county of Suffolk and State of Massachusetts, have 5 invented certain new and useful Improvements in Starting Devices for Internal-Combustion Engines; and I do hereby declare the following to be a full, clear, and exact description of the invention, such as 10 will enable others skilled in the art to which it appertains to make and use the same.

The present invention relates to a starting device for internal combustion engines, the purpose of the invention being to provide 15 the engine with means for controlling fluid pressure supplied from an auxiliary source, such as a compressed air tank, in such a way that the fluid pressure may be utilized to start the engine without interfering with 20 the normal functions thereof in case the engine fails to start in response to the ignition of a compressed charge remaining in a cylinder.

For this purpose, the invention is embodied in means for controlling the distribution of the fluid pressure in such a way that the pressure is admitted to the cylinders successively substantially at the beginning of and during the normal working 30 stroke in each cylinder, or, in other words, during the time when a compressed charge would be ignited and expanded by heat in the normal operation of the engine. The pressure is supplied to the cylinders through 35 ducts which are independent of the charge inlet passages, so that the fluid pressure does not, in any way, interfere with the normal functions of the engine which are naturally resumed as soon as the engine has been 40 started by the auxiliary fluid pressure. Taking, for example, a multi-cylinder, four-cycle engine, the distribution of the pressure is controlled by means acting in synchronism with the half time shaft which controls the 45 ignition, each cylinder receiving the pressure at alternate revolutions, there being no communication between the source of pressure and the cylinder during the suction and compression strokes. In this way, the fluid 50 pressure is admitted at the beginning of the normal working stroke and exhausted through the exhaust valve operating in the

normal way without interfering with the normal functions of the engine when running on combustion, and no shifting of the 55 cams, or other manipulation, is necessary after the engine has been started.

Figure 1 is a view in cross section of a device embodying the invention; Fig. 2 is a view half in elevation and half in longitudinal section on line a^2 , Fig. 1; Fig. 3 is a view similar to the sectional part of Fig. 2 showing the valve in a different position; Fig. 4 is a detail showing the movable valve member removed; Figs. 5 and 6 are views 65 similar to Figs. 2 and 1 showing a modification; Fig. 7 is a view of the modified construction of the valve removed from the casing; and Fig. 8 is an elevation, on a smaller scale, of the valve casing. 70

In the construction shown, I employ a single distributing valve common to all the cylinders, the ports 2, 3, 4, 5, 6, and 7 being arranged to be connected, as by pipes, with the cylinders of a six-cylinder four-cycle engine, 75 these ports leading from a chamber 1 which is provided with an inlet port 13, through which it is adapted to receive fluid pressure from any suitable source, as a tank of compressed air. The flow of compressed air 80 from the chamber 1 through the ports to the several cylinders is controlled by a distributing valve member arranged to travel in the casing so as to uncover the ports successively, this traveling member, in the case 85 of a four-cycle engine, being preferably arranged to rotate and to be connected when used in a four-cycle engine, with a shaft which revolves in harmony with the engine cycle, such, for example, as the half time 90 shaft which controls the cams and the ignition timer. In the construction shown, the traveling valve member 8 consists of a cylindrical shell provided with a port 11, Fig. 1, which, in the rotation of the valve 8, successively opens communication between the interior of the chamber 1 and the ports leading to the several cylinders. The port 11 is shown as adapted to overlap adjacent cylinder ports, so that one port is always open, 100 and, consequently, the valve will always stop in position to admit compressed air to a cylinder in which the piston is in position to start in desired direction. 95

The operation of the starting device may be described as follows: When a multi-cylinder engine stops, it may be, and usually is, possible to start the engine ahead by igniting the charge remaining in the cylinder which would have been last to operate had the engine been running, assuming that the engine is in perfect running order, so that said cylinder contains a charge of compressed gas. Such starting may be accomplished by moving the ignition timer back until the two contacts which have been last engaged are again brought together so as to produce the ignition in the desired cylinder. Similarly, the engine, if at least six cylinders are employed in the four-cycle type, can be reversed by moving the timer contact ahead and shifting the position of the valve operating cams. This self starting, however, cannot be absolutely relied upon, for the reason that there may be some failure in the ignition, or sufficient leakage in the cylinder to reduce the compression. With the auxiliary starting device embodied in this invention, however, the fluid pressure controlling device, which is arranged to operate in synchronism with the device which operates the traveling member of the ignition timing mechanism, will obviously stand with one port open, that port corresponding to the ignition contact which would operate if the engine were started on the spark. The fluid pressure, therefore, is admitted to the cylinder or cylinders in which the piston or pistons will travel outward to start the engine, the exhaust opening in the normal way at the end of the out-stroke, while the valve port for that cylinder becomes closed. The valve port to the succeeding cylinder in the series has been opened in the meantime, so that the fluid pressure is admitted successively to the cylinders in sequence to maintain the operation of the engine. This does not, in any way, interfere with the normal suction of the explosive mixture which takes place while the valve port is closed, so that ignition will take place as soon as the engine has been started, and has charged its cylinder with explosive mixture.

In the construction shown in Figs. 1 to 4, provision is made for starting the engine in the reverse direction, the valve member 8 being provided with a reversing port 12, 55 out of alignment with the port 11, and so located as to divert the air to the cylinder in which the piston was traveling on its compression stroke when the engine was stopped. To bring this reversing port into 60 operation, the valve is provided with means for moving it longitudinally in the chamber 1, the said valve being herein shown as having a spline or feather connection with the half time shaft 9, and an operating rod 65 or handle 10 which is longitudinally mov-

able for the purpose of shifting the valve. This reversal of the timing member must be accompanied, in a reversing engine of the four-cycle type, by a corresponding reversal of the valve cams, but, in other respects, the 70 operation is the same as that of the starting operation above described.

In Fig. 1, the valve is shown in full lines as in position to start the engine ahead, i. e., in the direction indicated by the arrow *a*. The firing sequence in this case, taking the valve port members as indicating the cylinders with which the ports communicate, is 5, 4, 3, 2, 7, 6. The engine has stopped, therefore, with the piston corresponding to 5, just at the beginning of its working stroke, and the piston corresponding to 6 just finishing. The compressed air acting on these pistons will start the engine ahead, closing port 6, and fully opening 80 port 5. The piston corresponding to 4 is on its compression stroke, and by the time this compression stroke has been completed, port 4 will be opened. Ports 3, 2, 7, and 6 are then opened successively. By having 90 the traveling port large enough to lap adjacent ports, communication will always be made with a piston which has not completed its working stroke, so that the engine can be started from any position in which it 95 has stopped. To reverse the engine, the port 12 is brought into alignment with the distributing ports, thereby opening communication with the port 4, as shown in dotted lines, Fig. 1. As above described, the 100 piston corresponding to port 4 is on its compression stroke in the ahead operation, so that if it is moved outward it will turn the crank shaft in the reverse direction. The valve will, therefore, begin to turn in the 105 direction of the arrow *b*, the piston corresponding to 5 moving back to the end of the cylinder ready to work when port 12 reaches port 5. Then follow 6, 7, 2, 3, etc., it being understood that the valve cams (in the case 110 of a four-cycle engine) have been shifted to reverse the functions of the regular inlet and exhaust valves.

In the construction shown in Figs. 5 to 8, the reversing feature is omitted, the valve 115 8 being provided with only one port, and there being no provision for longitudinal movement. The same reference numerals are used on these figures as on the figures previously described, and no further detailed description is believed to be necessary.

Claims:

1. An auxiliary fluid pressure starting device for a multi-cylinder engine consisting 125 of a traveling valve adapted successively to open ports communicating with the cylinders, the opening of the ports following the normal firing sequence; and means for shifting said valve to close the port which stands 130

open, and to open a port communicating with a different cylinder whereby the engine can be started in the reverse direction.

2. An auxiliary fluid pressure starting device for an internal combustion engine consisting of a traveling valve adapted successively to open ports communicating with the cylinders, the opening of the ports following the normal firing sequence, and the traveling valve being arranged to keep each port open during substantially the entire normal working stroke of each piston and to open the port next in sequence before closing the port which is then open.

15 3. An auxiliary fluid pressure starting device for a six cylinder engine consisting of a traveling valve adapted successively to open ports communicating with the cylinders, the opening of the ports following the normal firing sequence, and the traveling valve being arranged to keep each port open during substantially the entire normal working stroke of each piston; and means for shifting said valve to close the open port 25 and open a port communicating with a cylinder in which the piston is on its compression stroke.

4. In a starting device for a multi-cylinder internal combustion engine, the combination with the cylinders each provided with an inlet port; of means for opening said ports successively; each port in the series being opened prior to the closure of the port preceding; and an operating device therefor 35 timed to correspond with the engine cycle, whereby compressed air is admitted approximately at the time a charge would be exploded in the normal operation of the engine, and exhausted by the normal opening 40 of the exhaust port at the end of the working stroke.

5. A fluid controlling valve comprising a casing having an air inlet, and being provided with a series of outlet ports; a rotary valve in said casing having two openings in different planes; and means for moving the valve in the casing to cause one or the other opening therein to aline with the outlet ports; and means for rotating said valve.

50 6. A fluid controlling valve, comprising a casing having an air inlet and provided with a series of outlet ports; a rotary valve in said casing having two openings in different planes; a half-time shaft constructed to rotate said valve to cause the opening therein to aline with the outlet ports successively, and means for moving the valve in the cas-

ing to cause one or the other openings therein to aline with the outlet ports to permit reversing of the engine.

60 7. In a fluid pressure starting device for an internal combustion engine, the combination with the cylinders each provided with an inlet port; of valve mechanism adapted to be actuated by the engine to open said ports successively during the normal working strokes of the pistons; and means for changing the relation of said valve mechanism to the cylinder inlet ports to reverse the engine.

70 8. In a fluid controlling valve, the combination with a casing having a cylindrical bore and an air inlet, said casing also being provided with a series of outlet ports communicating with the bore of said casing and all having equal division walls between them and a half-time shaft projecting into one end of the casing, of a cylindrical valve in the casing and keyed to slide on the shaft, said valve having two openings in different planes and out of line with each other, and a rod projecting into the casing and connected with the valve to move the latter longitudinally in the casing to bring either of said openings in position to aline with the outlet ports successively when the valve is rotated.

90 9. In a fluid controlling valve, the combination with a casing having a cylindrical bore and an air inlet, said casing also having a series of outlet ports spaced an equal distance apart; of a cylindrical valve in the casing having an opening in its wall to aline successively with the outlet ports, the opening in the valve being longer than the face 95 of the dividing wall between two ports; and a shaft to rotate said valve.

100 10. In a fluid pressure starting device for an internal combustion engine, the combination with the cylinders, each provided with an inlet port; of a traveling member for successively opening said ports during the normal working stroke of the piston in each cylinder; and means for changing the relation of said traveling member to the 105 cylinder inlet ports to reverse the engine.

In testimony whereof, I have signed this specification in the presence of two subscribing witnesses.
